UNITED STATES PATENT OFFICE.

FREDERICK A. TEGELER, OF LA GRANGE, ILLINOIS.

RAIL-DRILLING DEVICE.

Application filed December 29, 1919. Serial No. 348,003.

To all whom it may concern:

Be it known that I, FREDERICK A. TEGELER, a citizen of the United States, residing at La Grange, in the county of Cook and 5 State of Illinois, have invented certain new and useful Improvements in a Rail-Drilling Device, of which the following is a description, reference being had to the accompanying drawings, which form a part of my 10 specification.

My invention relates to a device more especially adapted for drilling a single hole of any desired size, at each operation, in railroad rails; the device consisting of a truck 15 portion adapted to travel along the rails of a railroad and power-driven when desired; it also comprises drill holding and operating mechanism so secured to the truck-frame as to swing to the outside of the rail when in 20 operative position and to fold upward, over the truck, when in transporting or inoperative position.

The device contemplates means whereby the motive power of the truck may be employed for the drill-mechanism; together 25 with means whereby the drill mechanism will be properly secured to the rail to be operated on and the drill-bit and operating mechanism maintained in proper alignment 30 during the operating movement of the drill mechanism toward the rail.

The invention also contemplates means whereby the operation of the drill mechanism, the positioning of the drill and transmission of power to the drill-mechanism are 35 operable and controllable from the drill side of the device; while at the same time contemplating a construction wherein an adjustment of bit is obtained by means of a 40 hand-operated crank on the drill side of the device. My invention also contemplates a construction adapted to drill holes in the rail-web at any desired point relative to the base of the rail, by the mere adjustment of 45 adjustable elements or rests on the drill-frame.

The objects and advantages of my improved device will be more fully comprehended from the following detailed description 50 of the drawings, wherein:—

Figure 1 is a side elevation of my improved device illustrated in operative position on the rails, with the drill-bit in penetrating position.

Figure 2 is an end elevation of the drill 55 side of the device with portions of the frame and elements broken away.

Figure 3 is an enlarged side elevation and longitudinal sectional view of the drilling mechanism or portion of the device. 60

Figure 4 is a top plan view of the mechanism shown in Figure 3 with portions broken away to disclose other features or elements therebeneath.

In the particular exemplification of my 65 invention, it comprises a suitable truck-frame 10 provided with suitable journals for the track-wheels 11; the truck-frame being provided with a transversely disposed member 12, the outer ends whereof are provided 70 with suitable stub-axes or journals to receive the wheels 13 adapted to travel along the adjacent rail. The truck-frame is preferably shown provided with a suitable internal combustion motor, as at 14, the crank- 75 shaft whereof may be placed into operative relation with one of the truck-wheels so as to employ motive power for transporting the truck or device along the rails when desired as for example by chain and sprocket as 80 shown in my co-pending application Serial No. 348,002. One side of the truck is provided with ground-engaging wheels, as at 15, mounted on a suitable shaft supported by links 16 and 17; the link 16 being pivotally 85 secured at 18 to the truck-frame while the link 17 is shown pivotally secured at 19 to a bell-crank 20, which latter is pivotally secured to the truck-frame and enables the shaft carrying the ground-wheels 15 to be 90 raised or lowered into or out of ground-engaging position through the oscillation of bell-crank 20, which is adapted to be controlled by mechanism later to be described.

The ground-wheels 15 are disposed at 95 right angles to the main frame, as clearly shown in Figure 1, and therefore at right angles to the truck-wheels 11. With this construction, it is evident that when the ground-wheels are lowered from the position shown in Figure 1, the opposite or drill-mechanism carrying side of the device may be lifted from the track and enable the device to be transported or moved away from the rail; it being understood, of course, that when it is desired to move the device away from the rails, the drill mechanism carrying portion of the frame is then folded up over 100 105

the main or truck portion of the device, in a manner similar to that shown and described in my copending application Serial No. 348002.

5 The transversely disposed portions 12 of the main frame of the device are provided at suitable points with brackets or journal-boxes, as at 21, for oscillatingly securing the frame 22 of the drill mechanism to the main 10 frame of the device. The pivotal mounting of the drill-frame preferably consists in a rod or member disposed through the brackets or journal-boxes 21 secured to the main frame members 12 at opposite ends of the 15 device; with the drill-frame members 22 firmly secured or clamped to a journal or rod and at a point intermediate of the main frame members 12 at opposite ends of the device. The journal, disposed through the 20 brackets or journal-boxes 21, at points coincident with the points where frame members 22 are secured thereto, is preferably provided with segmental grooved wheels 23 adapted to rotate with the journal member. 25 The grooved segmental wheels 23, each have one end of the segment provided with a chain 24, whose free end has a coil spring secured thereto; while the latter, in turn is secured at a proper point to the main frame 30 10 of the device. The springs 25 are intended to constantly exert a pulling tension on the chains 24 and therefore on the segmental wheels 23, so that the drill-frame 22 will at all times be more or less yieldingly 35 suspended in either position, due to the pulling tension of the springs 25 exerted on the segmental wheels.

The outer ends of the journal member, whereby the drill-frame is oscillatingly supported on the main frame, is preferably provided with crank-arms, as shown at 26, to which suitable cables or rods 27 are secured; the cables or connecting means 27 being also secured to the ends of the bell- 45 cranks 20. With this construction, it is apparent that when the drill-frame 22 is elevated or swung over onto the main or truck-frame, thereby oscillating the crank-arms 26 in a direction toward the ground-wheel side 50 of the device, that the connecting means will be slackened so as to permit the ground-wheels to drop to ground-engaging position.

As the construction of the main or truck-frame, the ground-wheel mounting and controlling mechanism and the mounting of the drill-frame portion of the device, are all identical with said elements, their construction and operation as shown and described in my copending application, a more minute 55 description and statement of operation need not be here entered into; because in practice the drill-frame and mechanism of the present construction is adapted to be substituted for the drill-frame and drilling mechanism shown and described in my copending appli- 60 65

cation; such substitution being readily accomplished through the mere removal of the brackets or journal-boxes 21 and the supporting journal provided with the grooved segmental wheels 23; at the same time the outer section of the drive-shaft is removed and replaced by the outer drive-shaft section 28, more clearly disclosed in Figure 3; this outer drive-shaft section, like that disclosed in the copending application, being secured to the inner sections of the drive-shaft, by a suitable universal joint at a point in alignment with the pivotal point of the drill-frame on the main or truck-frame.

The outer drive-shaft section 28 is provided with a sprocket-wheel 29 adapted to receive sprocket-chain 30 which latter is disposed about a sprocket-wheel 31 which is slidingly mounted on a shaft 32 but adapted to transmit rotation thereto. The outer end of the drive-shaft 28 is supported by means of a suitable bracket 33, the lower ends whereof are suitably clamped onto the drill-frame members 22, see Figure 4. The sprocket-wheel 31 is maintained in vertical alignment with sprocket 29 by means of bracket 33, which is provided with a transversely disposed portion at the bottom adapted to take up against the hub of the sprocket 31; while the opposite end of the hub of the sprocket takes against the transversely disposed bracket or straps 34 which are clamped to the parallelly disposed drill-frame members 22. The shaft 32 is provided with a gear 35 which meshes with a gear 36 secured to the drill-spindle 37. The gears 35 and 36 are enclosed in a suitable casing or housing 38 which is provided with tapped portion adapted to receive screw-rod 39, see Figure 3. The screw-rod 39 is provided with a gear 40 shown in meshing relation with a pinion 41 which is secured against rotation on hand-operated shaft or crank 42; the shaft or crank 42 being rotatably mounted on a suitable frame or casting 43.

The casting 43 is socketed to receive the end of the screw-rod 39; the latter being provided with an enlargement or flange, as at 44, which will prevent longitudinal movement of rod 39 relative to casting 43; with the result that rotation of rod 39 will cause the gear-housing or casing 38 to travel lengthwise of screw-rod 39, thus enabling the housing or casing 38, with the drill-spindle 37, to be adjusted relative to the rail so as to compensate for drill-bits of different lengths.

The housing or casing 38 is formed to receive suitable ball or anti-friction bearings, as at 45, adapted to take up the end thrust on the drill-spindle.

With the construction of housing, the gearing and bearings may be constantly maintained in a suitable state of lubrication

The gear-housing or casing 38 is provided at opposite sides and both ends with lugs, as shown at 38^a, which are apertured to receive the frame members 22 so as to permit 5 the housing or casing to slide lengthwise of the frame-members. The transverse bottom portion of bracket 33 will prevent the too far forward movement of the housing or casing; while suitable stops at the ends of 10 the frame-members, as shown at 46, will prevent said housing from moving too far backwardly.

The normal relation between the rear end of the housing or casing 38 and the trans- 15 verse portion of bracket 33 is such as to permit a predetermined amount of forward movement of the housing or casing, as is evident from the construction as illustrated in Figures 3 and 4.

20 The casting 43 is provided with rearwardly disposed apertured lugs 47 (see Figures 2 and 4) which provide suitable bearings for a rotatable shaft 48. This shaft 48 is provided at a suitable point with spaced flanges 25 49, notched as shown in Figure 3 to receive the latch mechanism or dog carried by lever 50, whereby controlling relation between the lever and the shaft may be effected so as to enable the operator to rock shaft 48 in the 30 desired direction to actuate the elements now to be described. The outer ends of shaft 48 are provided with suitable crank-arms 51, rigidly secured thereto; and these arms 51 have a shaft 52 loosely mounted therein. 35 The ends of shaft 52 are provided with crank-arms 53, one of which terminates in a lever 54.

The free ends of the crank-arms 53 have 40 the ends of feed-hooks 55 pivotally secured thereto by means of stud bolts 56. The feed-hooks 55 extend forwardly and are adapted to contact with the opposite or inside of the rail, a distance below the horizontal plane of drill 57, substantially equal to the dis- 45 tance of the pivot points 56 from or below the center of the fulcrum point of feed-lever 50, namely the center of shaft 48, thereby providing a straight drilling feed-thrust which eliminates all unnecessary friction 50 and at the same time permits proper and true operation of the drill. The feed-hooks 55 are shown provided with clips 58 through which a rod 59 extends; the rod extending transversely of the device so as to be dis- 55 posed through the clips 58 on both feed- hooks 55 arranged at opposite ends of the machine. The rod 59 is threaded at its ends and provided with nuts whereby the clips 58 are firmly clamped at the desired point on 60 the hooks 55. The rod 59 is also provided with guides 60 loosely mounted on frame members 22 and rod 59 serves to hold the hooks 55 in proper alignment.

Each crank-arm 51 has a rod 61 pivotally 65 secured on the inner side thereof; the rod 61

being bent to extend over shaft 52 and thence back into substantially the same horizontal plane as the pivotal points thereof on crank-arms 51, as shown in Figures 3 and 4. The forward ends of the rods 61 are slidably 70 mounted in lugs on the sides of casing 38, whereby the rods are supported in proper horizontal position when the mechanism is in operative position. The forward ends of the rods 61 are shown threaded and pro- 75 vided with adjustable heads or tips 62, so as to permit the tips to be adjusted lengthwise of the rods 61 and adapt them to a long or short drill-bit; the tips 62 being locked in 80 adjusted position by means of a nut 63. The rods 61 are intended to have approximately the same length of stroke as the drill, but are arranged to move in the opposite direction so as to push against the rail when the 85 drill is being withdrawn from the drilled hole in the web of the rail.

The crank-arms 51 are shown provided with laterally disposed lugs 64 on the sides to which the crank 53 are secured; and these lugs 64 are provided with adjustable set- 90 screws 65. The set-screws 65 are intended to control the limit of movement of cranks 53 when in operative position and also to control the length of drill-stroke; the set-screws 65 controlling the distance between the centers of stud-bolts 56 and shaft 48; because in shortening the distance between the centers as described, the length of drill-stroke will also be shortened and produce an easier feed. From the construction shown and de- 95 scribed, it is apparent that when lever 50 is oscillated to the position as in Figure 3, shaft 48 will be rocked so as to move cranks 51 into the downwardly presented position shown in Figure 3, which, in turn, carries 100 the pivotal point of cranks 53 and therefore of lever 54 (which is made integral with one of said cranks) downwardly, thereby moving the free end of cranks 53 with the stud-bolt 46 into contact with set-screws 65, 105 whereby the feed-hooks 55 will be retracted and the hook-ends thereof brought into clamping engagement with the web of the rail on the side opposite to that of the drills. 110 With the feed-hooks 55 positioned as just described, the pressure exerted by the operator on lever 50 (such forward pressure having a tendency to induce further rocking of shaft 48 in a direction tending to swing the free ends of cranks 51 further to the right in 115 Figure 3) tends to force the drill-mechanism, namely the casing or housing 38 with the drill 57 toward the rail; the forward pressure being maintained until the drilling operation is completed, as shown in Figure 3.

The drilling operation having been completed, the operator then oscillates lever 50 toward the right in Figure 3 so as to rock shaft 48 sufficiently to oscillate cranks 51, to 120 125 130

which push-rods 61 are pivotally secured; the pivotal points of the push-rods being substantially aligned with the stud-bolts 56, thereby producing the same length of stroke in the opposite direction from that of the drills. As a result of this operation, the push-rods 61 (one on either side of the frame) will be brought against the web of the rail and caused to exert a retracting action on the drill-mechanism.

10 The frame members 22, 22 are each provided at a point coincident with the top of the rail to be operated on, with adjustable means, which, in the particular exemplification, is shown in the nature of set-screws 67 which may be held in adjusted position by means of lock-nut 68, see Figure 3. By screwing the set-screws 67 through the frame-members 22, they are brought into contact with the top of the rail and thereby limit or control the downward movement of the frame members and for that reason will control the horizontal plane of the drill-mechanism and drill-bit relative to the top of the rail. It is evident that with this construction, the operator may adjust the adjusting mechanism 67 so as to elevate or lower the drill-frame and mechanism carried thereby, relative to the ball of the rail so as to drill the hole or holes at the desired point.

In order to transport the device along the rails, the operator then oscillates lever 54 upwardly and rearwardly so as to swing the crank-portion 53 forwardly, causing feed-hooks 55 to be moved out of clamping relation with the rail. The forward movement of the feed-hooks 55 brings the clips or clamp-members 58 against the ball of the rail, preventing any further forward movement of hooks 55, with the result that the exerted pressure on lever 54 will cause the entire drill-casing or housing and mechanism carried thereby to be moved rearwardly along the frame members 22, a distance sufficient to have the drill-bit 57 and push-rods 61 clear the ball of the rail in the event that it is desired to elevate the drill-mechanism and drill-frame into transporting or folded over position.

In order to lubricate and cool the drill-bit 57 during its operation, I provide a suitable lubricating holder 69 mounted at any suitable point on the main frame of the device; and this lubricant holder is preferably provided with a flexible conduit or hose, as shown at 70 in Figure 1, whereby the lubricant and cooling medium is conveyed to a pipe or conduit 71 which is slidably mounted on the drill-housing or casing 33 in suitable guides 72. The inner or forward end of the conduit 71 terminates in a suitable nozzle which is provided with a valve as at 73. The conduit 71 is also suitably clamped to one of the push-rods 61 by means of

straps as at 74 so as to maintain the nozzle end of the conduit in proper relation with the rail during the drilling operation.

The conduit 71 is provided with a suitable valve at 75 which is operable by means of a stem 76 connected by a rod or other suitable means 77 to the rod 59. The valve and stem are so positioned that when the feed-hooks 55 are in clamping position, the valve 75 will be in open position and permit the lubricant or cooling medium to pass forward and be discharged, provided valve 73 is open. With the mechanism arranged as described, it will be seen that when feed-hooks 55 are moved into unclamping position, through the mechanism heretofore described, the valve 75 will be automatically closed and the further flow of lubricant or cooling medium thereby shut off and waste of the fluid during non-drilling operation prevented.

A lever 78 is suitably secured to the main frame of the device so as to be in easy reach of the operator handling lever 50. The main portion of lever 78 is adapted to control a suitable clutch arranged at a suitable point in the drive-shaft 28; while the latch portion 79 of this lever is adapted to control the operation of the motor 14.

The sectional drive-shaft 28 is preferably extended beyond bracket 33 in order that it may receive a suitable crank for the purpose of cranking or starting the motor 14.

I have shown and described what I believe to be the simplest and best adaptation of my invention; but it is apparent that certain modifications may be made in details of construction without, however, departing from the spirit of my invention.

What I claim is:—

1. A rail drilling device, comprising a truck, a drill-supporting frame disposed transversely of the truck and hingedly secured at a point intermediate of the sides of the truck so as to swing vertically and be disposed to the outside of the rail when in operative position and to fold upwardly across the truck toward the opposite side thereof when in transporting position, a drill-casing mounted on the drill-supporting frame to slide lengthwise thereof, and means whereby the drill-casing may be given movement independent of the drilling stroke thereof.

2. A rail drilling device, a truck provided with rail-engaging wheels, a drill frame hingedly secured at one end to said truck to swing vertically and adapted to extend to the outside of the rail when in operative position and above the truck when in transporting position, a drill-casing slidably mounted on the drill frame, means oscillatably secured to the drill-casing, rail-engaging members carried by said means, one portion of said members being adapted to en-

gage with the side of the rail opposite to that on which the drill-casing is located when said means is oscillated in one direction, while the other portion of said members is adapted to engage with the side of the rail on which the drill-casing is located when said means is oscillated in the opposite direction and the first mentioned portion of the members thereby moved out of rail-engaging position, and means whereby the drill-casing may be given independent movement toward or away from the rail and the length of drilling stroke controlled.

3. A rail drilling device, comprising a truck, a drill-frame composed of a pair of elongated spaced members each hingedly secured at one end to said truck to swing vertically and adapted to be disposed beyond the outside of the rail when in operative position, a drill-casing slidably mounted on the drill-frame members, hand operated means whereby the drill-casing may be given movement independent of the drill-stroke thereof to compensate for varying lengths of bits, and means whereby power may be transmitted to the drill-bit carried by said drill-casing.

4. A rail drill device, comprising a truck, a drive-shaft disposed transversely of the truck, a drill-frame secured to said truck, a drill-casing slidably lengthwise of the drill-frame, sprocket and chain connection between the drive-shaft and the drill-casing for transmitting power, said connection being adapted to permit longitudinal movement of the drill-casing, and means having threaded relation with the drill-casing whereby the drill-casing may be given movement independent of the drilling stroke thereof.

5. A rail drilling device, comprising a truck, a drill-frame, secured to said truck at an intermediate point so as to extend beyond the rail, a drive-shaft carried by said truck and said drill-frame, a drill-casing slidably lengthwise of the drill-frame, means for controlling the extent of movement of the drill-casing relative to said drill-frame, flexible means intermediate of the drive-shaft and drill-casing and movable lengthwise of the drive-shaft whereby power is transmitted to the drill-bit and longitudinal movement of the drill-casing lengthwise of the drill-frame permitted, and means whereby the drill-casing may be given independent movement of the drilling stroke and the degree of movement controlled.

6. In a rail drill device of the character described, a drill-frame, a driving shaft, a drill casing slidably mounted on the drill-frame so as to move lengthwise thereof, driv-

ing mechanism intermediate of the drive-shaft and the drill casing whereby power is imparted to the drill-spindle within said casing, said driving mechanism permitting a horizontal movement of the drill-casing, feed-hooks carried by said drill-casing adapted to engage with the opposite sides of the rail operated on, the engagement of the hooks with the rail and their points of connection with the drill-casing being so correlated that a straight drill thrust is provided, push-rods carried by said drill-casings and adapted to engage the adjacent side of the rail operated on, and means for controlling the drill-casing and the push-rods whereby the push-rods are moved toward the rail while the drill-casing is moved in the opposite direction.

7. A rail drill device, comprising a truck provided with motive power, a drill-frame, a drive-shaft carried by the truck and said drill-frame, a drill-casing slidably mounted on said drill-frame and provided with a drill-spindle, a counter-shaft carried by said drill-casing and having operative relation with the drill-spindle within said casing, power-imparting means operatively connected with the drive-shaft and said counter-shaft adapted to move lengthwise of the drive-shaft and said counter-shaft, whereby power is imparted from the drive-shaft to said counter-shaft, housing for said counter-shaft and drill-spindle, and hand-operated means operatively connected with said housing whereby the latter, with the drill-spindle, may be given independent movement.

8. In a rail drill device of the character described, a drill-frame, a drill-casing slidably mounted on the drill-frame so as to move in a horizontal direction, said drill-casing being provided with a counter-shaft whereby motive power is transmitted to the drill-spindle, carried by the drill-casing, a drive-shaft, means intermediate of the drive-shaft and said counter-shaft for transmitting power to the counter-shaft, said means being movable lengthwise of the drive-shaft and counter-shaft, feed hooks carried by the drill-frame and adapted to engage with the opposite side of the rail operated on, a valved lubricant or cooling medium conveying conduit, and means intermediate of the valve of said conduit and the feed hooks whereby the flow of lubricant is controlled by the position of the feed hooks.
